UNITED STATES PATENT OFFICE.

AUGUST MEYER, OF MINNEAPOLIS, MINNESOTA, AND PHILIP R. WALSH, OF ST. LOUIS, MISSOURI, ASSIGNEES, BY MESNE ASSIGNMENTS, TO DUPLEX HOLDING COMPANY, OF ST. LOUIS, MISSOURI, A CORPORATION OF MISSOURI.

METHOD OF AND APPARATUS FOR TREATING TIMBER AND THE LIKE.

1,422,119.

Specification of Letters Patent. Patented July 11, 1922.

Application filed August 3, 1921. Serial No. 489,471.

To all whom it may concern:

Be it known that we, AUGUST MEYER, a citizen of the United States, and resident of the city of Minneapolis, county of Hennepin, and State of Minnesota, and PHILIP R. WALSH, a citizen of the United States, and resident of the city of St. Louis, State of Missouri, have invented certain new and useful Improvements in Methods of and Apparatus for Treating Timber and the like.

Our invention relates to improvements in method of and apparatus for treating timber and the like, and has for its primary object an apparatus for a method of treating a predetermined portion or the lower or butt end of telephone, telegraph poles, piling, posts and similar timbers.

A further object is a method of treating timbers and the like with a preservative, whereby a deeper penetration of the preservative in the wood cells, ducts or vessels is possible and at the same time not losing any of the more volatile essential oils.

In the drawings, Fig. 1 is a side elevation of one form of apparatus by means of which our improved method may be carried out.

Fig. 2 a plan view of the false cover for the treating chamber made use of.

In carrying out our invention we employ an apparatus consisting of a treating chamber 3 and a storage or working tank 4. The tank 4 is preferably constructed so that it has the same capacity as the treating tank 3. By this construction we are enabled to determine the amount of liquid admitted to the treating tank 3. Secured in the bottom of the tank 4 is a pipe connection 5 which is connected to a pipe 6. Between the pipe connection 5 and the pipe 6 is a valve 7. This is for the purpose of shutting off the flow of the preservative which is contained in the tank 4. The pipe 6 is connected to the lower end of the treating tank 3 by means of a pipe connection 8. The pipe 6 extends upwardly above the valve 7 and has secured to it the T 9 and to this T is secured a valve 10, the purpose of which will be explained later.

Immediately above the T 9 is secured the valve 11 and extending above this is a pipe connection 12 which leads into the upper portion of the tank 4. Located in the lower portion of the tank 4 is a heating coil 13

which is connected to a pipe 14, which in turn is connected to a steam boiler 15. Interposed between the pipe 14 and coil 13 is a valve 16 for regulating the flow of steam into the coil 13. Located in the bottom of the treating tank 3 is a steam coil 17 which is connected to the pipe 14 by means of a branch pipe 18. The branch pipe 18 is also provided with a valve 19 for the purpose of admitting or closing off steam to the coil 17. Raised a short distance above the bottom of the treating tank 3 is a false bottom 20. This bottom is provided with perforations and is supported by means of braces 21. The upper edge of the treating tank 3 is provided with a flange 22 through which bolts 23 extend. These bolts pass through the flange 24 of the cover 25 and are for the purpose of making an air and water tight joint between the cover and tank. Secured to the upper end of the treating tank 3 and below the flange 22 is a pipe connection 26 which is connected to an air compressor 27, communication between the treating tank 3 and compressor 27 being governed by means of the valve 28. Secured to the upper portion of the treating tank 3 is a second pipe connection 29 which is connected to an exhaust or vacuum pump 30, and between the exhaust or vacuum pump 30 and tank 3 is interposed a valve 31. Connected to the pipe 29 and opening into the bottom of the tank 3 is a branch pipe 32. The compressor 27 is connected to the steam pipe 14 by means of a branch pipe 33 which has a valve 34 for governing the admission of steam; while the vacuum pump 30 is connected to the steam pipe 14 by means of a branch 35, the steam being admitted to the pump by means of a valve 36. Within the tank 3 is located a false top 37 which is provided with openings 38, this is for the purpose of holding down timbers when placed therein and preventing them from floating when the preservative is admitted to the treating chamber. This false top may be either of sufficient weight to hold down the timbers or may be secured within the treating tank by any well known means. The purpose of the vacuum pump and pipes 29 and 32 is to create a vacuum within the treating tank, while the compressor 27 is for the purpose of creating pressure therein.

Secured to the tank 3 is a gauge 39 by means of which the level of preservative in

the tank can be readily determined. Our method consists in first placing within the treating tank 3 a number of timbers to be treated. The false cover 37 (if the timbers 5 are shorter than the tank) is then placed in position, and the cover secured in place. The valves 7, 10, 11 and 28 are closed tightly while the valve 31 is opened. The vacuum pump 30 is then placed in operation and creates a partial vacuum in the tank 3, this 10 partial vacuum also has a tendency to draw out air contained in the cells and ducts of the timber and thus create a partial vacuum therein. When a sufficient vacuum 15 has been obtained, (depending on the character of the timber being treated) the valve 31 is closed, this maintains the vacuum within in the treating chamber 3 and also in the cells of the timbers. The valve 7 is then 20 opened and the liquid preservative in the container or tank 4 is drawn forcibly into the treating tank 3, this force is due to the atmospheric pressure behind it and it not only rises in the treating chamber 3, but is 25 also drawn up into the cells and ducts of the wood from which the air has been exhausted and seals the vacuum therein. When a sufficient level of liquid has flowed in the treating chamber 3, the valve 7 is closed, and the 30 valve 28 opened and the air compressor 27 is placed in operation. This creates air pressure in the upper portion of the treating chamber 3 which pressure is transmitted to the preservative through the openings 38 35 formed in the false cover 37. This pressure causes the preservative to be forced into the cells and ducts of the wood, thus completely filling them. When the cells have been thus filled, the air pressure is left on and the 40 valve 11 is opened—the air pressure now forces the excess preservative upward through the pipes 6 and 12 and back into the tank 4, after which the cover 25 is removed, the false cover 37 is withdrawn and the treated timbers removed from the treating 45 chamber.

In the event that the timbers used are green, they may be seasoned by turning steam into the coil 17 in the tank 3. After 50 the steam has been let on a certain time, the valve 10 is opened and a large amount of moisture is permitted to escape in this way. The valve 10 is then closed and the valve 31 opened. The vacuum pump 30 is then placed 55 in operation and the timbers further seasoned in a vacuum which further draws out moisture. After all the moisture has been withdrawn in this way, the vacuum is maintained by closing the valve 31 and the previously 60 described operation, opening the valves 7 and 28 and starting a flow of preservative, and the air pressure is repeated. In this way it is possible to maintain a deep penetration of preservative in green timber. 65 This was not possible before. Another im-

portant feature of our treatment is that by the use of our apparatus and method, all the essential oils contained in the preservative, such as coal tar creosote are retained and driven into the wood.

In the open tank process, which is now used, two operations are necessary, first, in immersing the timbers in a highly heated creosote oil and afterwards immersing it in a cold creosote oil or preservative. Heating of 70 this preservative to the degree necessary in the open tank process drives off the more volatile oils in the form of vapor. These oils which are lighter or more volatile, are the ones that possess the highest toxic value, while the 75 heavier oils which remain have less toxic value and also less penetrating power than the lighter or thinner oils, thus it will be seen that by the open tank process less penetration is obtained and furthermore, that portion of the preservative which penetrates the cells the deepest has the least toxic value, while by our process we may heat the preservative just sufficiently to cause it to flow 80 freely and still not cause any vaporization of the lighter oils, thereby obtaining a deep 85 penetration of oils which have the highest toxic value and consequently the timbers are preserved to a much greater degree and will last longer than those treated by the 90 open tank method which is now generally in use.

While we have shown and described an apparatus consisting of one working tank and one treating tank, yet it is obvious that 100 we may use any number of such tanks and we may place our treating tank in any position except the horizontal. Any type of air compressor or vacuum pump or steam boiler may be employed and any number. The treating tank may be of any shape or size and may have its upper end opened for filling as illustrated, or it may be provided with a side opening and a closure for said opening. The tank may be placed above the ground or be placed in a pit as shown. It is also obvious that the working tank may be provided with a gauge. An essential feature 110 of our apparatus is an air and water tight tank that is capable of having a partial vacuum formed therein, in which air pressure can be set up, and the disposition of this tank at an angle to the horizontal preferably in an upright or vertical position, whereby a certain predetermined portion of a timber 115 may be treated; and an essential feature of our method is the treatment of a predetermined portion of a timber by one application of the preservative, utilizing the vacuum and air pressure to obtain a deep penetration 120 of the preservative and the preservation of all the oils of high toxic value.

It will be noted that in the practicing of our method, that the vacuum is first created in the ducts and cells throughout the entire 130

length of the timbers and when the timbers are enveloped to the predetermined height with the preservative, the preservative seals the vacuum in the cells and ducts only in 5 that portion of the timbers enveloped, then when air pressure is created in the treating tank, the cells and ducts above the enveloped portion of the timbers are filled with compressed air which prevents the upward passage 10 of the preservative beyond the enveloped portion, while on the enveloped portion the combined forces of the vacuum on one side of the preservative and air pressure on the other forces it deeply into the 15 cells and ducts practically filling them completely. We thereby by our improved method, obtain a deep penetration of the preservative and also a uniform distribution of the preservative throughout the portions 20 of the timber treated.

Having fully described our invention, what we claim is:

1. The herein described process of treating a predetermined portion of a piece of timber 25 with a preservative liquid by immersing a terminal portion thereof to the desired extent in the treating liquid, and producing a pressure above the liquid and about the free extending portion of the piece of timber to 30 cause a penetration of the liquid.

2. The herein described method of treating at one and the same time predetermined portions of timbers with a preserving liquid which consists in assembling a plurality of 35 such timbers in a substantially upright position and immersing the terminal portions thereof to the desired extent in the treating liquid and producing a pressure above and

acting on the surface of the liquid and about the free extending portions of the timbers 40 to cause a penetration of the liquid into the immersed portions of the bodies of the timbers.

3. The herein described method of treating a timber with a preserving liquid which 45 consists in placing it within an air and liquid tight tank, creating a vacuum in the tank to withdraw vapors from the cells of the timber, thereafter admitting a sufficient quantity of the treating liquid to immerse a 50 terminal portion of the timber to the desired extent and producing a pressure above the liquid and about the free extending portion of the timber to cause a deep penetration of the liquid into the immersed portion of the 55 body of the timber.

4. An apparatus for the simultaneous treatment of predetermined portions of a number of timber poles, piling and the like comprising a treating tank arranged in a 60 substantially upright position and provided with a closure means and uninterrupted from top to bottom to permit the introduction of a number of timbers into the tank, which are supported at their lower 65 ends, a liquid connection leading to the tank near its bottom through which is delivered a preservative liquid, an air pressure line connection with the tank at the upper portion thereof, and a vacuum line connection 70 with the tank.

In testimony whereof, we have signed our names to this specification.

AUGUST MEYER.
PHILIP R. WALSH.
